UNITED STATES PATENT OFFICE

JESSE C. HAYES, OF KITTANNING, PENNSYLVANIA

ROPE ANCHOR

Application filed May 26, 1930. Serial No. 455,840.

This invention relates to certain new and novel improvements in devices for securing one end of a rope to a support such as a clothes line rope to a post or the like, the device being termed, for the sake of convenience, a "rope anchor".

The primary object of this invention is to provide a device whereby a rope may be conveniently secured to a support or other suitable structure whereby the rope may be suitably anchored to the support, the same being especially adaptable for clothes lines, or for any other suitable purpose.

Other objects and advantages of the invention will become apparent, during a study of the following description, taken in connection with the accompanying drawings, wherein:

Figure 1 is a front elevational view of my improved device illustrating its manner of use.

Fig. 2 is a side elevational view thereof.

Fig. 3 is a top plan view of the device.

My improved attaching or anchoring device is preferably formed from a single strand 25 of wire 5 having end portions 6 and 7 respectively bent inwardly toward one another, parallel with the intermediate portion of the wire to provide at the top and bottom of the device substantially U-shaped recesses 30 through which the shanks of a nail or other suitable fastening element F may be passed and driven into a suitable support S for securing the device in fixed position on the support.

One of the end portions 6 merges into a horizontal laterally disposed extension 7 which in turn is bent inwardly upon itself to provide an open ended loop portion 8. The free end of the loop terminates in a downwardly and inwardly extending portion 9 which in turn is bent upwardly as at 10 to provide a substantially V-shaped rope receiving part.

The end 7 may be bent outwardly or offset and at said offset is bent downwardly to provide a hook or substantially inverted V-shaped rope receiving portion 12.

In actual practice, a portion of the rope may be engaged in the U-shaped loop portion 8, the rope then passed downwardly to

be received in the hook or inverted V-shaped end 12, after which the rope is then passed upwardly to be received in the V-shaped or hook like extension 10, the rope then being pulled as for example, on a horizontal plane 55 as suggested in Fig. 2 to be secured at its opposite end in a suitable manner to a similar device as that just described, or to any other device whereby the free portion of the rope may be tautened or stretched as in the 60 manner of providing a clothes line.

From the foregoing, it is also apparent, that my device may be used in conjunction with the ropes of awnings for securing the three portions of the awnings to the door 65 jamb or the like in lieu of the devices now in use.

It is thought that from the foregoing description, the construction, use, advantages and utility of a device of this character will 70 be had by those skilled in the art without a more detailed description.

Even though I have herein shown and described the preferred embodiment of my invention, it is to be understood that the same 75 is susceptible to changes fully comprehended by the spirit of the invention and the scope of the appended claims.

Having thus described my invention, what I claim as new is:—

1. In a device of the character described, an anchoring member formed from a single strand of wire looped at its opposite ends to accommodate retaining elements whereby the device may be secured to a support, one of said ends intermediate its end and the adjacent looped portion merging into a horizontally disposed open ended loop portion in turn merging into a vertically disposed rope receiving hook, and the other of said ends merging into an inverted V-shaped rope receiving hook portion.

2. In an anchoring device of the class described, a substantially elongated split loop-like member formed from a single strand of wire, said member at one end thereof, merging into an inverted V-shaped rope receiving hook, said member at its opposite end merging into a lateral extension in turn merging into a substantially U-shaped rope

receiving loop, one leg of said loop being bent at right angles to extend parallel with the first-mentioned rope receiving hook portion, said one leg in turn merging into a substantially V-shaped rope receiving hook.

3. In an anchoring device of the character described, a substantially looped member, provided adjacent each end thereof with a substantially V-shaped receiving hook, said hooks extending reversely with respect to one another, and said loop member adjacent one of said hooks being provided with a lateral substantially U-shaped rope receiving loop.

In testimony whereof I affix my signature.

JESSE C. HAYES.
